CLAIM

The ornamental design for an auxiliary article carrier for a truck bed storage compartment, as shown and described.

DESCRIPTION

FIG. 1 is a perspective view of an auxiliary article carrier for a truck bed storage compartment showing my new design, with the closure flap in partially opened condition;

FIG. 2 is a perspective view thereof on a reduced scale, it being understood that the broken lines are for illustrative purposes only and form no part of the claimed design; and

FIG. 3 is an enlarged cross-sectional view thereof taken alone line 3—3 in FIG. 2.
